RING TRAVELER

Maurice Lee Bolton, Philadelphia, Pa., assignor to
 U. S. Ring Traveler Co., Providence, R. I., a corporation of Rhode Island

Application December 11, 1942, Serial No. 468,717

4 Claims. (Cl. 57—125)

This invention relates to ring travelers of the vertical type for employment in spinning or twisting.

The device is primarily for use in spinning and twisting fine wire of steel, copper, brass and similar material, although the same could readily be used in connection with the spinning and twisting of thread or yarn.

Ring travelers heretofore in use are not adapted for use in the spinning and twisting of wire and are objectionable, if usable at all, due to the formation of spirals or kinks in the wire as it travels from the guide rolls or guide eye and under the traveler head to the bobbin or spool on which the wire is being wound.

The formation of objectionable kinks or spirals are avoided by the use of the present device, due to the fact that practically the only bend made in the wire or material during its passage from the feed rolls or guide eye to the finished wound bobbin is one substantially in the form of an arc when the wire passes downwardly through the opening in the head of the traveler and out through the opening in the shank thereof; this rather than around and under the head of the traveler, as heretofore, and then to the bobbin or spool.

Difficulty in winding and twisting with kinks or spirals in the material is thereby avoided.

Also by the use of the present traveler a more upright position is maintained during the revolution of the traveler around the ring than where the wire or thread or yarn passes beneath the head and around one edge, as heretofore.

In the present invention there are no sharp bends or turns whatsoever in the material as in travelers heretofore in use.

In travelers heretofore in use, the traveler binds on the ring, being canted in operation, but with the present traveler it is maintained in an upright position during its travel around the ring and all canting or binding on the ring is avoided, thereby saving wear and tear on both the ring and traveler.

Another object of the invention is the provision of ring travelers which do not require frequent replacement and which are capable of long use without diminishing in efficiency or effectiveness, which travel smoothly and evenly and without vibration or jerkiness, which maintains the tension on the thread even and smooth and at the proper and desirable degree, and cause no variation or unevenness in the twist of the yarn and which eliminate objectionable strains under tension due to the formation of

kinks or spirals in the material in its passage through the traveler.

Another object of the invention is to avoid excessive friction or cramping of the traveler in its course around the ring occasioned by passing the thread beneath the traveler, as heretofore, whereby the latter is tilted bringing it in contact with the ring at an angle thereby causing wear and tear on both the traveler and ring.

It will be seen, therefore, that in the use of the present traveler all objectionable sharp bends of the material is avoided such as are present in the previous travelers.

To the attainment of the foregoing and other objects which will appear as the description proceeds, reference may be had to the accompanying drawing, in which:

Fig. 1 is a perspective view of a twister ring showing my novel ring traveler in operating position thereon;

Fig. 2 is a sectional view of the ring with traveler thereon;

Fig. 3 is a perspective view of the ring traveler; and

Fig. 4 is a sectional view on the line 4—4 of Fig. 1.

As shown, 10 is a vertical twister ring with the ring traveler 11 mounted in operative position thereon.

The traveler is formed from a metallic blank and comprises a vertical shank 12 formed with a head or horn portion 13 with a downwardly inclined lip portion 14. Substantially centrally of the head or horn portion 13 a hole or opening 15 is provided through which the wire or yarn 18 first passes from the feed roll or guide eye (not shown) in a substantially straight line and thence toward the spindle or spool through the hole or opening 19 in the shank 11. Formed upon the lower end of the shank and integral therewith is a foot portion 16 having an upturned portion or lip 17.

The fine wire, thread, filament, yarn, strand or other material 18 extends downwardly through the hole 15 and thence through the groove or guide 20 formed on the inner face of the traveler and connecting the two openings out through the hole 19 to the bobbin or spool.

It will be observed that due to the location and arrangement of the holes 15 and 19 relative to each other, the material will pass from the roll or guide eye to the bobbin or spool with no sharp bends, and that the traveler will move in a circular path around the ring without any canting or cramping or binding of the traveler on the

ring and thus any grooving, excessive heating, or other disadvantage resulting from frictional contact of the traveler with the ring are avoided, and the material is maintained remote or away from the face of the ring 10.

Having thus fully described my invention what I claim as new and desire to secure by Letters Patent of the United States is:

1. A traveler for vertical twister rings comprising a vertical shank, a lip integral with the lower end of the shank, a head portion integral with the upper end of the shank, said head and shank portions each having an opening therethrough through which the material being twisted and wound is passed.

2. A traveler for vertical twister rings comprising a vertical shank, a lip integral with the lower end of the shank, a head portion integral with the upper portion of the shank, an opening formed in the head portion and an opening formed in the shank portion, the openings being so spaced and arranged with relation to each other that the material being twisted passes through the opening in the head in a substan-

tially straight line and out through the opening in the shank at an angle to said line.

3. A traveler for vertical twister rings comprising a vertical shank, a lip integral with the lower end of the shank, a head portion integral with the upper end of the shank, said head and shank portions each having an opening therein through which the material being twisted and wound is passed, the inner face of the traveler between the two openings being grooved to form a channel or guide for the material from one opening to the other.

4. A traveler for vertical twister rings comprising a vertical shank, a lip integral with the lower end of the shank, a head portion integral with the upper end of the shank, means in the shape of an opening formed in said head, and means in the shape of an opening formed in the shank, said means cooperating with each other to permit the passage of the material being twisted through said means to the spool or bobbin without the formation of a sharp bend in the material.

MAURICE LEE BOLTON.
